UNITED STATES PATENT OFFICE

HOWARD M. BARBER, OF PAWCATUCK, CONNECTICUT, ASSIGNOR TO C. B. COTTRELL & SONS COMPANY, OF WESTERLY, RHODE ISLAND, A CORPORATION OF DELAWARE

WEB FEEDING MECHANISM

Application filed April 12, 1930. Serial No. 443,748.

My invention comprises certain improvements in web feeding mechanism whereby webs of heavy or light stock can be successfully fed by providing the web feed rolls 5 with removable web margin engaging rings which may be retained on the rolls when heavy material, such as magazine stock, is to be fed and which may be removed when light or weak material, such as newspaper 10 stock, is to be fed.

My invention further comprises a change speed drive for the said web feed rolls, which drive includes a change gear mechanism for driving the feed rolls at one angular speed 15 when the rings are retained and at a greater angular speed when the rings are removed, whereby the web whether it be of heavy stock or of light stock may be fed at a predetermined speed by said rolls.

My invention more particularly comprises a gear train drive including two coaxial driving gears of different diameters and a shiftable intermediate gear arranged to be brought into mesh with either one of said 25 driving gears.

A practical embodiment of my invention is represented in the accompanying drawings, in which

Fig. 1 represents a diagrammatic end elevation, showing the web feed rolls with their web margin engaging rings retained, and the shiftable intermediate gear in mesh with the driving gear for feeding the web of heavy stock;

Fig. 2 represents a detail side view of the same;

Fig. 3 represents a diagrammatic end elevation showing the web feed rolls with their web margin engaging rings removed and the shiftable intermediate gear in mesh with the other driving gear, for feeding a web of light stock;

Fig. 4 represents a detail side view of one of the web feed rolls, showing one of the web margin engaging rings mounted thereon;

Fig. 5 represents a cross section taken in the plane of the line V—V of Fig. 4, looking in the direction of the arrows;

Fig. 6 represents a detail side view of one

of the web feed rolls with the web margin engaging ring removed therefrom;

Fig. 7 represents a side view of one of the web margin engaging rings.

In the web feeding mechanism illustrated in the accompanying drawings I have shown four web feed rolls 1, 2, 3, 4. In Figs. 1, 2 and 4 the web feed rolls are provided with web margin engaging rings 5 removably mounted thereon. These rings are shown as split, for facilitating their mounting on and removal from the web feed rolls. The rings are also shown as having overlapping ends and as being removably secured on the web feed roll by means of screws 6. These removable web margin engaging rings 5 may be of any predetermined thickness, to cause the roll to properly feed a web of heavy stock.

In Fig. 1, I have shown a heavy web 7 as passing around the web feed rolls in engagement with the removable web margin engaging rings on said rolls, while in Fig. 3, I have shown a thin web 8 as being passed around these web feed rolls with the web margin engaging rings removed from said rolls.

The drive for the web feed rolls is herein shown as a gear train in which two coaxial driving gears 9 and 10 are shown as mounted on a shaft 11 which carries a gear 12 driven, in the present instance, from a pinion 13. An intermediate gear 14 is shiftable to two different positions in two planes, to bring it into mesh with either the driving gear 9 or the driving gear 10, according to whether the heavy web or the light web is to be fed by the web feed rolls. In Fig. 1 the shiftable intermediate gear 14 is shown in one position where it meshes with the driving gear 9 while in Fig. 3 it is shown in another position where it meshes with the driving gear 10. In both of these positions the shiftable intermediate gear 14 meshes with the wide faced gear 15, which gear 15 is at all times connected with the web feed rolls through the train of gears 16, 17, 18, 19, 20 and 21.

From the above description it will be seen that by simply shifting the position of the intermediate gear 14 to bring it into engagement with either the driving gear 9 or the

driving gear 10 of the gear train, the web feed rolls may be driven at a predetermined surface speed with or without their web margin engaging rings so that the web whether it be

5 of heavy material or light material is driven at said predetermined speed, thereby permitting the feeding of webs of heavy or light stock in the same web feeding mechanism.

10 It is evident that various changes may be resorted to in the construction, form and arrangement of the several parts without departing from the spirit and scope of my invention, and hence I do not intend to limit myself to the particular embodiment herein

15 shown and described, but

What I claim is:—

1. In a mechanism for feeding webs of heavy or light stock, a web feed roll, web margin engaging rings removably mounted thereon, and a change speed drive for said roll.

2. In a mechanism for feeding webs of heavy or light stock, a plurality of web feed rolls, web margin engaging rings removably mounted thereon, and a change speed drive for said rolls.

3. In a mechanism for feeding webs of heavy or light stock, a web feed roll, web margin engaging rings removably mounted thereon, and a change gear drive for said roll.

4. In a mechanism for feeding webs of heavy or light stock, a plurality of web feed rolls, web margin engaging rings removably mounted thereon, and a change gear drive for said rolls.

5. In a mechanism for feeding webs of heavy or light stock, a web feed roll, web margin engaging rings removably mounted thereon and a gear train drive for said roll, including therein driving gears of different diameters, and means for operatively connecting up the one or the other of said driving gears.

45 6. In a mechanism for feeding webs of heavy or light stock, a plurality of web feed rolls, web margin engaging rings removably mounted thereon and a gear train drive for said rolls, including therein driving gears of different diameters, and means for operatively connecting up the one or the other of said driving gears.

55 7. In a mechanism for feeding webs of heavy or light stock, a web feed roll, web margin engaging rings removably mounted thereon and a gear train drive for said roll, including therein driving gears of different diameters, and a shiftable intermediate gear arranged to be brought into mesh with either

60 one of said driving gears.

8. In a mechanism for feeding webs of heavy or light stock, a plurality of web feed rolls, web margin engaging rings removably mounted thereon and a gear train drive for

65 said rolls, including therein driving gears of

different diameters, and a shiftable intermediate gear arranged to be brought into mesh with either one of said driving gears.

9. In a mechanism for feeding webs of heavy or light stock, a web feed roll, web margin engaging rings removably mounted thereon and a gear train drive for said roll, including therein coaxial driving gears of different diameters, and a shiftable intermediate gear arranged to be brought into

75 mesh with either one of said driving gears.

10. In a mechanism for feeding webs of heavy or light stock, a plurality of web feed rolls, web margin engaging rings removably mounted thereon and a gear train drive for

80 said rolls, including therein coaxial driving gears of different diameters, and a shiftable intermediate gear arranged to be brought into

85 mesh with either one of said driving gears.

11. In testimony, that I claim the foregoing as my invention, I have signed my name this

11th day of April, 1930.

HOWARD M. BARBER.
